UNITED STATES PATENT OFFICE.

OSCAR GASSETT, OF BOSTON, MASS., ASSIGNOR TO THE UNION SWITCH AND SIGNAL COMPANY, OF HARTFORD, CONN., AND PITTSBURG, PA.

ELECTRO-PNEUMATIC RAILWAY-SIGNAL.

SPECIFICATION forming part of Letters Patent No. 276,021, dated April 17, 1883.

Application filed February 1, 1881. (No model.)

To all whom it may concern:

Be it known that I, OSCAR GASSETT, a citizen of the United States, residing in Boston, in the county of Suffolk and State of Massachusetts, have invented certain new and useful Improvements in Electro-Pneumatic Railway-Signals, of which the following is a specification.

My invention relates to that class of alarms and signals which are employed in connection with railways, and are designed to be automatically actuated by a moving train.

The general object of my invention is to cause an alarm to be sounded at any designated point—such as a station or highway-crossing—upon the approach of a railway-train, and to continue the operation of the same until the train, in its progress, has passed the point where the apparatus is situated, and which it is designed to guard, after which the operation of the alarm will be discontinued.

The invention further has for its object the exhibition of a visual signal at some convenient point near the railway, a short distance in advance of the position occupied by the train at the moment when the alarm should commence to be sounded, which signal will be maintained automatically in a position indicating danger, except at such times as the alarm is in operation, whereby in case said alarm fails to sound properly after the train has reached the proper point its further progress in the direction of the crossing will be arrested by the non-withdrawal of the danger-signal, while, on the other hand, if the alarm is performing its office properly the danger-signal will be withdrawn and a safety-signal exhibited, thus permitting the train to proceed on its way.

To this end my invention consists in the combination of a bell or gong, a hammer or striker for sounding the same, a motor consisting of a piston moved to and fro within a cylinder by the force of compressed air or other fluid under pressure for actuating said hammer, a valve for controlling the admission of air to the said motor, the movements of which are determined directly or indirectly by the action of an electro-magnet. The electro-magnet itself is in turn controlled from a

distance by means of an electric generator and a circuit-closer appertaining to a moving railway-train, whereby the action of the said generator upon the electro-magnet is determined.

The invention further consists in a secondary signal, preferably a visual signal, which is controlled by an independent electric circuit and circuit-closer attached to the alarm mechanism in such a manner that the said circuit-closer will be operated synchronously with the audible signal.

The invention further consists in certain combinations and details of mechanism, which will be hereinafter more fully described.

In the accompanying drawings, Figure 1 represents the essential portions of the alarm mechanism, its motor, and controlling apparatus, together with its attached circuit-closer for operating the secondary signal. Fig. 2 is a theoretical diagram, representing the general arrangement of the electric circuits with reference to the railway, and also their connection with the controlling electro-magnets of the signals; and Fig. 3 is a detached view of a portion of the mechanism, exhibiting certain details not clearly shown in Fig. 1.

The several figures of the drawings are not designed to exhibit the several parts of the apparatus in their actual relative positions and dimensions, but the latter are so delineated that each may be clearly understood, and the intermediate steps by which the electric current is rendered available to control the movements of the bell-hammer and circuit-closer may be readily comprehended.

Referring to Fig. 1, M is the electro-magnet which controls the alarm apparatus. When the alarm is in its normal condition—that is to say, silent—a continuous current of electricity traverses the coils of the electro-magnet M, and maintains the same in a constantly-magnetic condition, thereby holding the armature R in contact with its poles, in opposition to the force of the retracting-spring S. Upon the opposite extremity of the armature-lever R' is a stop, P, (see Figs. 1 and 3,) against which rests a projecting stud, a', upon the back of one of the arms, A', of a four-armed escapement. A', A², A³, and A⁴ represent the respective arms of the said escapement, the

axis of which is connected with the plug of a stop-cock or valve, C, and has also a pinion, K', mounted thereon. The stop-cock C, escapement, and pinion K' tend to revolve continuously in the direction indicated by the arrows, by reason of the force exerted by the descending weight W, operating through suitable intermediate mechanism—namely, the drum J', axis J, and toothed wheels K² and K'. This mechanism, however, is held in check so long as the current through the electro-magnet M remains uninterrupted by the stud a', which rests against the stop P on the armature-lever R'. If now the electro-magnet M is demagnetized, it will release its armature R, and the opposite end of the lever R' will consequently descend by the action of the spring S, carrying with it the stop P, and this movement will disengage said stop from the stud a' upon the escapement-arm A', and allow the latter to pass freely over and beyond the former. The escapement-arms and stop-cock C are now free to rotate in the direction shown by the arrow by the action of the weight W and the intervening mechanism through one-fourth of a complete revolution. The projection a² upon the arm A², which is placed upon the arm in such a position as to engage the stop P, provided the armature of the electro-magnet is released, now comes in contact with the said stop and arrests the revolution of the escapement. When the electro-magnet is again rendered magnetic the stop P is caused to return to its original position, thus disengaging the arm A². The escapement now revolves through another one-fourth of a revolution, and is again arrested by the engagement of the stop P with the stud a³, which occupies the same relative position upon the escapement-arm as the stop a'. As the path of the stop a⁴ is also coincident with that of the stop a², it will readily be understood that a movement of the armature-lever R', due either to the charging or discharging of the magnet M, will cause the plug of the stop-cock C to make one-fourth of a complete revolution. The position of the arms of the escapement with reference to the aperture N in the plug of the stop-cock C is such that when either of the arms A' or A³ are arrested by the stop P the stop-cock is closed, while if either the arms A² or A⁴ are arrested the stop-cock is open. The valve or stop-cock C, which has been described, controls the admission of fluid under pressure—for example, compressed air—which is contained in a suitable reservoir, V, through a pipe, v v, to the valve-chest E of an ordinary reciprocating motor or engine consisting of a cylinder, P, and piston, P', the function of which is to actuate a bell-hammer or striker, I, mounted upon a lever, I', which is pivoted at Q. It will be understood, therefore, that whenever the electro-magnet M is traversed by a continuous electric current the stop-cock C is closed, and the hammer I consequently remains at rest, while if the current

through the electro-magnet is interrupted or diverted the stop-cock C is opened by the rotation of the escapement, and the hammer I is set in action to sound an alarm. The valve e, which controls the admission of the compressed air alternately to the opposite ends of the working-cylinder P, is automatically actuated by the to-and-fro movement of the piston itself in a well-known manner, which is sufficiently illustrated in the drawings. 75

In order to do away with the necessity of frequently rewinding the weight W by manual power, I have devised mechanism (shown in Fig. 1) whereby such rewinding is effected automatically when required. The toothed wheel K² is mounted upon a sleeve upon the shaft J, which carries a drum, J', upon which the cord w, which sustains the weight, is wound. A wheel, H, having ratchet-shaped teeth, is rigidly attached to the drum J'. A pawl, Y, is pivoted at y' to the lower end of the short arm of the hammer-lever I', and when the hammer is operated by the motor the pawl Y, moving to and fro, engages with the successive ratchet-teeth of the wheel H, and thus pushes the same forward, causing it to rotate in the direction indicated by the arrow a distance of one or more teeth at each stroke of the hammer. The motor E is thus made to rewind the weight W every time it is set in operation. This is effected without interfering with the movements of the toothed wheel K² by means of mechanism to be described. When the weight W is descending the dog k engages with one of the teeth of the ratchet-wheel H, and this causes the wheel K² to turn with the axis J. When the weight W has been elevated to the required height by the action of the pawl Y, as hereinbefore described, a device for disengaging the pawl from the ratchet-wheel H is automatically brought into action. This may be effected in various ways. In the mechanism for this purpose illustrated in the figure the cord w, which supports the weight, carries a button, X', which, when the weight is sufficiently elevated, lifts the arm L' of a three-armed lever turning upon the fulcrum Z. The arm L² is thus brought against a projection, y', of the pawl Y, which is thereby thrown out of gear with the ratchet-wheel H, and in consequence the winding of the weight is arrested. When in the performance of its function the weight W has descended a sufficient distance to render rewinding necessary a second button, X², also carried by the weight-cord w, depresses the arm L', thus causing the arm L³ to throw the pawl Y again into gear, when the operation of rewinding is repeated, as hereinbefore explained. 110

F is a circuit-closing device arranged to be actuated by compressed air. It consists of an elastic diaphragm, D, secured at its edges to a shallow metallic cup, G, which thus forms a chamber behind the diaphragm. p' is a contact-point mounted upon the center of the

diaphragm D, and p^2 is a fixed contact-point mounted in close proximity thereto. When the stop-cock C is opened and the motor set in action to ring the bell compressed air is 5 also admitted to the chamber G through the branch pipe g, which presses the elastic diaphragm D outward and brings the points p' and p^2 into contact, thereby closing an independent electric circuit, which necessarily remains closed by the pressure of the air as long 10 as the motor continues in operation. The function of this circuit-closer will be hereinafter explained.

In the diagram, Fig. 2, I have illustrated an 15 application of the mechanism which I have described to a highway-crossing over which passengers and vehicles pass across the railroad-track upon the same level, and it therefore becomes desirable that an efficient alarm or 20 audible signal should be provided to give notice of the approach of a train. The location of the crossing is indicated by the dotted lines at J.

T T represent the railroad-track, the opposite lines of rails of which are electrically separated or insulated at the points $t' t'$ at or near the crossing J, and also at the points $t t$ at some distance away—say half a mile, more or less—in the direction from which the trains approach the crossing, as indicated by the arrows, 30 thus forming an insulated section of track between the said points. At the latter point, most distant from the crossing, a battery, B', is placed, having its opposite poles connected with the respective lines of rails of the track 35 T T leading toward the crossing, and at the opposite end of the insulated section of track the terminal wires of the coils of the electro-magnet M, which controls the alarm apparatus, are likewise attached to the respective opposite lines of rails. Consequently a continuous 40 current from the battery B' flows through the respective rails of the track T T and the coils of the electro-magnet M. A train approaching the crossing, upon reaching the end of the 45 insulated section of track at $t t$, forms a metallic connection between the opposite lines of rails, which connection continues until the entire train has passed beyond the crossing J and the insulated joints $t' t'$. During this 50 period the current of the battery B' is short-circuited by the wheels and axles of the train, which constitute a movable circuit-closer, and the electro-magnet M is consequently demagnetized and releases its armature, thereby setting 55 the alarm-bell B in automatic operation in the manner hereinbefore explained. At the same time the action of the compressed air upon the diaphragm D closes the circuit between the contact-points p' and p^2 and brings the independent battery B' into action, the current 60 of which traverses an electro-magnet, M', and causes it to actuate a visual signal, O, placed alongside the railway at such a point as to be visible to the engineer of the train at some distance 65 before the train reaches the crossing J. The visual signal which is thus operated by

the electro-magnet M' may be of any suitable or well-known construction, the only essential requirement being that it shall indicate "safety" when the circuit through the electro-magnet is completed, and "danger" when the circuit is interrupted. I have shown a conventional representation of such a signal at O in Fig. 2, which will sufficiently serve to illustrate the principle of its operation. The return-circuit of the battery B' may be formed by one of the rails of the track T T, as shown in the figure; or a separate wire may be erected especially for the purpose, although this is not in general necessary.

It will be understood from the foregoing description that upon the approach of a train to the crossing J the alarm-bell B will be set in operation as soon as the train passes beyond the insulated joints $t' t'$; but if by reason 85 of any failure in the supply of compressed air the alarm fails to operate, then the circuit of the battery B' will not be closed, and consequently the signal O will continue to indicate "danger," thereby warning the engineer of the 90 train to approach the crossing carefully, or to take such other precautions to avoid accident as may be necessary or desirable.

The reservoir V may be supplied with compressed air by any suitable means, and when 95 once fully charged it will contain sufficient to operate the apparatus for a considerable time. One convenient method of charging the reservoir is by means of a special air pump or compressor driven by a donkey-engine and mounted upon a car, which may be transported from one signal to another upon the railroad, and connected with the reservoirs, when by setting the pump in operation they can be quickly charged with compressed air.

I do not desire to confine myself to the precise mode of construction of the various parts of the mechanism shown in the figures, as these may be greatly modified without departing from the principle of my invention.

I claim as my invention—

1. The combination, substantially as hereinbefore set forth, of a bell or gong, a hammer or striker for sounding the same, a piston moved to and fro within a cylinder by fluid-pressure for actuating said hammer, a valve for controlling the admission of fluid under pressure to said cylinder, which valve is automatically actuated by the movements of the piston, an independent valve for controlling the admission of the fluid under pressure to the said automatic valve, and an electro-magnet for controlling the opening and closing of the independent valve.

2. The combination, substantially as hereinbefore set forth, of a valve for controlling the admission of fluid under pressure to a signal-operating mechanism, mechanism independent of the signal-operating mechanism impelled by a constant force tending to alternately open and close said valve, an escape- 125 ment whereby said independent mechanism is

alternately released and held in check according to the position of an electro-magnetic armature, and an electro-magnet whereby the position of said armature may be controlled 5 from a distant point.

3. The combination, substantially as herein-before set forth, of a valve for controlling the admission of fluid under pressure to a signal-operating mechanism, mechanism impelled by 10 a constant force for opening and closing said valve, an electro-magnetic armature by the movements of which said mechanism is alternately released and held in check, and mechanism for storing up or accumulating said constant force, which mechanism is impelled by 15 said signal-operating mechanism when in action.

4. The combination, substantially as herein-before set forth, of a signaling mechanism 20 actuated by fluid-pressure, an electric circuit-closer likewise actuated by fluid-pressure, and a valve which simultaneously sets in action both the signaling mechanism and the circuit-closer by the admission thereto of fluid under 25 pressure.

5. The combination, substantially as herein-before set forth, of an audible signal which is automatically set in action by a moving train while traversing a determinate section of a rail- 30 way-track by means of an electric generator, a circuit-closer actuated by the moving train, and an electro-magnet, and a visual signal situated at the entrance of said section of track, which signal is actuated or controlled by an 35 electric current transmitted by a circuit-closer operated synchronously with the audible signal.

6. The combination, substantially as herein-before set forth, of an audible signaling mechanism and an electric circuit-closer, both si- 40

multaneously actuated by fluid-pressure, with an independent signaling mechanism operated by an electric current controlled by said circuit-closer.

7. The combination, substantially as herein-before set forth, of a motor and a circuit-closer both capable of being actuated by fluid-pressure, a reservoir containing fluid under pressure, and a valve whereby said fluid is admitted to the motor and to the circuit-closer, thus 45 causing them to be simultaneously actuated.

8. The combination, substantially as herein-before set forth, of a motor and a circuit-closer both capable of being actuated by fluid-pressure, a reservoir containing fluid under pressure, a valve whereby said fluid is admitted to the motor and the circuit-closer, thus causing them to be simultaneously actuated, and an electro-magnet capable of being actuated by 55 an electric current from a distant point for 60 controlling said valve.

9. The combination, substantially as herein-before set forth, of a motor and a circuit-closer both capable of being actuated by fluid-pressure, a reservoir containing fluid under pressure, a valve whereby said fluid is admitted to the motor and the circuit-closer, thus causing them to be simultaneously actuated, an electro-magnet for controlling said valve, and an electric circuit and circuit-closer actuated by 65 a moving train for controlling said electro-magnet.

In testimony whereof I have hereunto subscribed my name this 31st day of January, A. D. 1881.

OSCAR GASSETT.
